BRUSH

Filed March 30, 1928

Fig. 1.

UNITED STATES PATENT OFFICE

CHARLES BERTOLA, OF LA ROCHE-SUR-FORON, FRANCE

BRUSH

Application filed March 30, 1928, Serial No. 265,887, and in France April 13, 1927.

This invention relates to a brush, which may be used with advantage for varnishing or otherwise treating objects the surfaces of which have portions which are recessed or difficult of access, such as radiators for heating purposes, grids or the like.

The brush comprises a stock or handle, and a brush head and bristles, and has for its characteristic feature a construction in which the brush head and bristles are connected to the handle by means of a universal joint with means for locking it in any desired position.

The accompanying drawing shows, by way of example, one constructional embodiment of a brush, made according to the invention—a flat form of brush being illustrated.

Figure 1 is a front elevation of the brush, with the bristles extending in alignment with the handle.

Figure 2 is a corresponding side elevation of Fig. 1.

Figure 3 is a front elevation with the bristles inclined towards the side with respect to the handle.

Figure 4 is a side elevation showing the bristles inclined transversely with respect to the handle, and

Figure 5 is an end view, with the handle removed.

The bristles 1 are fixed by means of rivets 3 in a sheath or holder 2, which may for example be of metal, open at both extremities and having a flattened cylindrical shape, the outline of which in cross section is constituted by long straight parallel sides 31 connected by semi-circular ends 32.

Into the sheath 2 is inserted a removable base or plug 4, of metal for instance, which may be rendered rigid therewith by means of a screw 7 passing through a smooth hole in the casing and into a screw threaded hole in the plug 4.

The plug just mentioned is provided with two parallel lugs or eyes 5 and 6 furnished with two smooth holes in alignment with one another. 9 is a screw bolt passing through the holes and furnished with a head at one end and a nut 11 at the other.

Between the two lugs 5 and 6 is a perforated connector piece 10 through which the screw

9 passes. 17 is another screw bolt passing through a perforation in the piece 10 and through smooth holes in two lugs 15, 16 on a cap or ferrule 13 fixed to one of the extremities of the handle 12 by nails 14. The screw bolt 17 is provided with a head and with a nut 18 in the form of a conic frustum.

The two screw bolts 9 and 17 are perpendicular to one another in such a way that the sheath 2 and the cap 13 are interconnected by means of a universal joint of which all the parts lie substantially within the interior of the projected surface 40 of the sheath 2, as may be clearly seen on inspecting Fig. 5, in which the handle 12 is supposed to be removed and will occupy the position shown in dot and dash lines.

The nuts 11 and 18 moreover, when screwed home, allow for the sheath and the piece 10 to be locked at will in any adjusted positions.

By reason of this universal connection, the bristles 1 can be set into an inclined position in any plane with respect to the handle 12, thus enabling the varnishing or treatment to be easily or conveniently effected of surfaces which it would be difficult or impossible to varnish or treat with the use of an ordinary rigid brush. The brush replaces advantageously the three rigid bent brushes utilized for painting radiators. By reason of its universal metallic joint, there is no risk of its breaking at the bent portion owing to too much force being used. By removing the screw 7, the sheath 2 may be separated from the plug or base 4, for instance for changing the bristles of the brush after wear. It also permits in addition for the bristles to be used completely.

In some cases the sheath may not be removable but would then be formed in one with the base or plug.

Other means may be employed than those indicated for attaching the bristles 1 to the sheath 2 and the ferrule or cap 13 to the handle 12.

The mass or bundle of bristles may have a different shape to that indicated.

What I claim is:

In a paint brush, a flat brush head having

bristles therein, lugs of substantially the width of the flat brush head extending therefrom in spaced positions longitudinally thereof and having apertures therethrough, a handle also having a flat head, a cap secured to and conforming with the flat head of the handle, lugs extending in substantially parallel positions from the long sides of the said cap and having apertures therethrough, a connector member extending between the said lugs and having bearing apertures at right angles to each other adjacent the ends thereof, and bolts extending through the apertures in the said lugs and also through the said bearing apertures in the connector member for connecting the brush head and handle to each other through the said connector member forming a universal joint between the said parts, the said lugs and bolts all lying substantially within the projected confines of the said brush head when the brush head is in alignment with the handle.

In testimony whereof I have signed my
name to this specification.

CHARLES BERTOLA.
